CLAIM

(22) Filed: **Apr. 17, 2019**

The ornamental design for a portable USB light tube, as shown and described.

DESCRIPTION

Related U.S. Application Data

(63) Continuation of application No. 29/566,612, filed on Jun. 1, 2016.

FIG. 1 is a perspective view of a portable USB light tube showing my new design;

(51) **LOC (12) Cl.** **26-02**

FIG. 2 is a bottom view of the portable USB light tube of FIG. 1;

(52) **U.S. Cl.**

FIG. 3 is a bottom plan view of the portable USB light tube of FIG. 1;

USPC **D26/38**

FIG. 4 is a top plan view of the portable USB light tube of FIG. 1;

(58) **Field of Classification Search**
